PADLOCK

Henry Hansen, Chicago, Ill., assignor to Chicago Lock Company, Chicago, Ill., a corporation of Illinois

Application October 5, 1936, Serial No. 104,005

3 Claims. (Cl. 70—38)

The present invention relates generally to padlocks. More particularly the invention relates to that type or variety of padlock which comprises as the main or essential elements thereof (1) a casing having a pair of shackle receiving bores extending through the top face thereof and embodying a third bore of larger diameter extending through its bottom face and intersecting one of the shackle bores; (2) a longitudinally slidable U-shaped shackle, having a long leg which is slidably and rotatably mounted in the other shackle bore and a short leg which is adapted in response to inward shift of the shackle into a locked position to fit within the one shackle bore; (3) a key-operable tumbler equipped plug which is rotatably mounted in the lower end of the large bore and is shiftable from a locked position into a padlock unlocking position; and (4) a plug controlled locking bolt which is rotatably mounted in the inner end of the large bore and embodies means for securing the short leg of the shackle within said one shackle bore and thus holding the shackle in its locked position.

One object of the invention is to provide a padlock of the type under consideration which includes a bolt controlled locking pin for securing the long leg of the shackle against axial displacement in its bore when the shackle is in its locked position.

Another object of the invention is to provide a padlock of the last mentioned character in which the locking bolt is urged into its locking position by a spring and is operatively connected to the key-operable tumbler equipped plug by way of a lost motion lug and groove connection which permits the plug to be rotated into its unlocked position independently of the locking bolt after shift of the bolt into its unlocked position, and the locking pin for locking the long leg of the shackle against axial movement in its bore when the shackle is in its locked position serves additionally to limit outward sliding movement of the long leg of the shackle and also to hold the bolt in its unlocked position while the shackle is in its unlocked position.

A further object of the invention is to provide a padlock which is generally of new and improved construction, consists of but a small number of parts and may be manufactured at a low and reasonable cost.

Other objects of the invention and the various advantages and characteristics of the present padlock will be apparent from a consideration of the following detailed description.

The invention consists in the several novel features which are hereinafter set forth and are more particularly defined by claims at the conclusion hereof.

In the drawing which accompanies and forms a part of this specification or disclosure and in

which like numerals of reference denote corresponding parts throughout the several views:

Figure 1 is a vertical longitudinal sectional view of a padlock embodying the invention;

Figure 2 is a transverse sectional view on the line 2—2 of Figure 1;

Figure 3 is a vertical longitudinal sectional view showing the shackle, the locking bolt, and the plug in their unlocked positions;

Figure 4 is a transverse sectional view taken on the line 4—4 of Figure 3 and showing the manner in which the locking pin serves when the shackle is in its unlocked position to retain the locking bolt in its unlocked position;

Figure 5 is a transverse sectional view taken on the line 5—5 of Figure 3 and showing the construction and arrangement of the spring-pressed holding or retaining device for the key-operable tumbler equipped plug;

Figure 6 is a vertical transverse sectional view on the line 6—6 of Figure 1; and

Figure 7 is a perspective of the locking bolt and plug.

The padlock which is shown in the drawing constitutes the preferred embodiment of the invention. It is adapted for general padlock use and comprises a casing 8, and a shackle 9. The shackle, as shown in the drawing, is U-shaped and comprises a short leg 10 and a long leg 11. The body 8 is in the form of a die-casting and has a flat top face 12 and a flat bottom face 13. It is laterally elongated, as shown in Figures 2, 4 and 5, and has in addition to the flat top and bottom faces 12 and 13 three bores 14, 15 and 16. The bore 14 is formed in one side of the casing 8 and serves as a mounting or journal for a lock plug 17 and a locking bolt 18. It is of uniform diameter from one end thereof to the other and extends from a point beneath the top face 12 of the casing to and through the bottom face 13. The plug 17 is located in the lower portion of the bore 14 and the locking bolt 18 is disposed above the plug and fits within the upper portion of said bore 14. The bore 15 is formed in the same side of the casing 8 as the bore 14. It is adapted to receive the short leg 10 of the shackle 9 when the shackle is in its locked position and is smaller in diameter than, and is located outwardly of, the bore 14. As shown in Figure 3, the bore 15 extends downwards from the flat top face 12 of the casing 8 and intersects the upper outer portion of the bore 14. The bore 16 is formed in the other side of the casing 8 of the padlock and extends downwards from the flat top face 12 to a point directly above the bottom face 13 of the casing. It is the same in diameter as the bore 15 and forms a bearing in which the long leg 11 of the shackle 9 is slidable longitudinally as well as rotatable. A compression spring 19 is disposed in the lower end of the bore 16.

16 and operates when the locking bolt 18 is rotated by the plug 17 into its shackle releasing position, as hereinafter described, to shift the shackle upwards into its unlocked position. In 5 this position of the shackle the short leg 10 is disposed above the top face 12 of the casing, as shown in Figure 3, and the shackle is free to swing sidewise about the axis of the long leg 11. A locking pin 20 serves to retain the lower end 10 of the long leg 11 of the shackle within the upper end of the bore 16 when the shackle is shifted by the spring 19 into its unlocked position. This pin 20 is slideable longitudinally in a horizontally extending bore 21 in the upper portion of the 15 casing 8. As shown in the drawing, the bore 21 extends between and intersects the upper ends of the bores 14 and 16.

The plug 17 has a longitudinal slot 22 for a key 23 and is provided at its lower or exposed end with a head 24. The latter is substantially flush with the bottom face 13 of the casing 8 and fits within an annular recess 25 around the lower end of the bore 14. The plug is locked against rotation in the casing 8 by means of a set of key 25 operable plate tumblers 26. The latter are mounted in a U-shaped frame 27 so that they are slideable transversely with respect to the plug. The frame 27 fits snugly in a transverse socket 28 in the central portion of the plug 17 and is similar in design and construction to that which is shown in United States Letters Patent No. 1,644,092. A spring (not shown) is associated with the frame and operates in conjunction with laterally projecting lugs on the tumblers to force the tumblers outwardly in opposite directions and so that the end parts thereof are normally disposed in a pair of grooves 29 and 30. The latter are positioned diametrically opposite one another and extend along and lengthwise of the bore 14. 35 The groove 29 is located in the central portion of the casing 8 and extends upwards from the recess 25 to a point beneath the horizontally extending bore 21 for the longitudinally slideable locking pin 20. The groove 30 extends upwards from the annular recess 25 and the upper end thereof intersects the bottom or lower end of the bore 15 for the short leg 10 of the shackle. When the key 23 is inserted through the key slot 22 the tumblers 26 are shifted so that the end parts thereof are withdrawn from the longitudinal grooves 29 and 30. While the tumblers are in this position the plug is free so that it may be rotated 90° by the key 23 from a locked position (see Figure 1) into an unlocked position (see Figure 3). Upon return of the plug to its locked position and removal of the key from the key slot the aforementioned spring which is associated with the frame 27 forces the tumblers into locked relation with the grooves 29 and 30 and thus prevents rotation of the plug relatively to the casing. Rotation or turning of the plug in excess of 90° is prevented by means of a lug 31 which is formed integrally with the padlock casing 8. As shown in Figure 6, this lug 31 is disposed in the inner portion of the annular recess 25 and fits within an arcuate groove 32 in the upper or inner portion of the plug head 24. When the plug is in its unlocked position, as shown in Figure 3, the key cannot be removed from the key slot 22 due to the fact that the tumblers are in alignment as far as the end parts thereof are concerned and cannot slide transversely of the plug due to the contact of their ends with the periphery of the bore 14. To remove the key from the plug it is necessary to rotate the plug into its locked posi-

tion. The plug is held against axial displacement in the bore 14 by means of a crescent-shaped holding device 33. This device, as shown in Figure 5, fits within an annular groove 34 in the inner end of the plug 17 and is urged outwards by means of a compression spring 35 into a position wherein the outer margin of the central part thereof is disposed in an annular groove 36 around the central portion of the bore 14. The spring 35 fits within a hole 37 in the lug 17 and surrounds an inwardly extending stem 38 on the holding device 33. The stem fits within the hole 37 and causes the holding device to rotate with the plug. It is formed as an integral part of the device and is disposed directly opposite to the groove 30 when the plug is in its unlocked position. In order to remove the plug 17 from the bore 14 it is only necessary to bring the plug and shackle into their interlocked positions and then insert a pin (see Figure 3) through the bore 15 into the upper end of the tumbler receiving groove 30. When the pin is in this position it may be manipulated so as to force the holding device 33 inwards into a position wherein the outer margin of the central part thereof is disengaged with respect to the annular groove 36 around the bore. After shift of the holding device into such a position the plug is free so that it may be removed from the bore 14. By having the upper end of the groove 30 intersect the bore 15 ready access to the holding device 33 may be had through the bore 15 for plug releasing purposes when the shackle is in its unlocked position. The holding device because of its location or arrangement on the plug 17 can only be released when the plug is in its unlocked position. In this position of the plug the key is held in fixed relation with the plug due to locking of the tumblers, as previously pointed out, and serves as a handle whereby the plug may be readily pulled from the bore upon release of the device. In view of the fact that access to the holding device 33 can only be had via the bore 15, it is impossible to release the device and thus free the plug when the shackle is in its locked position. The enlarged head 24 at the lower end of the plug 17 serves as a closure for the lower end of the tumbler receiving groove 30 and prevents access to the holding device via the lower end of the groove 30. The holding device 33 exemplifies means accessible via the bore 15 for releasably holding the plug 17 against axial displacement in the bore 14. 45 The locking bolt 18 is controlled by the key-operable lock plug 17 and constitutes the means by which the shackle is held or locked in its locked position with the short leg 10 thereof in the bore 15. It is rotatably mounted in the upper end of the bore 14 and embodies an arcuate cut-out 39 and a lock dog 40 over the cut-out. The dog, as shown in Figure 1, fits within a notch 41 in the lower end of the short leg 10 of the shackle when the shackle and locking bolt are in their locked positions, and locks the short leg of the shackle in the bore 15. The notch 41 is spaced a slight distance above the extreme lower end of the short leg of the shackle and faces in the direction of the bore 14. The cut-out 39 extends substantially half-way around the bolt and accommodates and forms a pocket for the extreme lower end of the short leg of the shackle 70 when the locking bolt and shackle are in their locked position and the dog 40 is in interlocked relation with the notch 41. The dog 40 is in the form of a flange and has a notch 42 in one end thereof. This notch leads to the cut-out 39 and 75

is adapted when the locking bolt is rotated by the key operable lock plug 17 into its unlocked position (see Figures 3 and 4) to register with the bore 15 and releases the short leg of the shackle so that it is free to move out of said bore. When the short leg of the shackle is in the bore 15 and the locking bolt is rotated into its locked position the dog 40 moves into the notch 41 and effects an interlocking connection whereby the shackle is secured in place. When the locking bolt is rotated into its unlocked position the dog 40 rotates out of interlocked relation with the notch 41 and the notch 42 is brought into registry with the bore 15. Upon registry of the notch 42 with the bore the short leg of the shackle is free, as previously pointed out, so that it may move out of the bore 15. The upper end of the locking bolt 18 has a cylindrical socket 43 for a cylindrical stud 46. The latter is formed as an integral part of the padlock casing 8. It is disposed in the extreme upper end of the bore 14 and forms an auxiliary bearing for the locking bolt. The lower end of the bolt, as shown in Figure 6, has a cylindrical socket 45 for a cylindrical stud 46 on the upper or inner end of the key-operable lock plug 17. The stud 46 is formed as an integral part of, and is centrally positioned with respect to, the upper end of the plug and forms an interfitting connection with the socket 43 whereby the plug and locking bolt are held in axial alignment and against transverse displacement one with respect to the other. The plug is connected to rotate the locking bolt 18 into its unlocked position by means of a lug 47. This lug is formed integrally with, and projects upwardly from, the upper end of the plug 17. It is located outwardly of the stud 46 and fits within an arcuate groove 48 in the lower end of the locking bolt 18. The lower end of the locking bolt embodies an integral shoulder forming abutment 49 which defines one end of the groove 48. When the plug and locking bolt are in their locked positions the lug 47 abuts against the abutment 49, as shown in Figure 7, and a driving connection is formed between the plug and the bolt whereby the locking bolt is caused positively to rotate into its unlocked position when the plug is turned by the key into its unlocked position. The groove 48 extends throughout an arc of approximately 180° and forms with the lug 47 a lost motion connection whereby the plug may be returned to its locked position independently of the locking bolt. A coil spring 50 serves to rotate the locking bolt 18 into its locked position when the latter, as hereinafter described, is released by the locking pin 20. This spring fits within an annular groove 51 in the lower end of the locking bolt. The groove, as shown in Figures 1, 3 and 6, is disposed directly above the groove 48 into which projects the lug 47 on the upper end of the key operable lock plug 17. One end of the spring 50 is anchored in a hole 52 in the plug and the other end of the spring projects radially outwards and fits within the upper end of the tumbler receiving groove 29 in the central portion of the padlock casing 8.

The lock pin 20 has a three-fold purpose. First, it serves to limit outward movement of the long leg 11 of the shackle when the shackle is in its unlocked position, second, it serves when the shackle is in its unlocked position, as shown in Figure 3, to lock the locking bolt 18 against return to its locked position by the spring 50; and third, it operates when the shackle and locking bolt are in their locked positions to lock the

long leg of the shackle in the bore 16. The inner end of the pin 20 is rounded and engages the outer periphery at the upper end of the locking plug. The outer end of the pin is rounded also and projects into the bore 16. The long leg 11 of the shackle 9 has a notch 53 for receiving the outer end of the pin 20 when the shackle is in its locked position and has an annular groove 54 for receiving the outer end of the lock pin when the shackle is in its unlocked position. The groove 54 is formed in the lower end of the short leg 11 of the shackle and is aligned with the horizontally extending bore 21 when the shackle is in its unlocked position. The notch 53 is located a short distance above the groove 54 and registers with the bore 21 when the shackle is in its locked position. It faces the notch 41 for the lock dog 40 and communicates with the groove 54 by way of a channel 55. The latter is comparatively shallow and is of less depth than the notch 53. When the shackle is in its locked position, as shown in Figure 1, the inner end of the lock pin 20 abuts against the upper end of the locking bolt 18 and the outer end of the pin and fits and seats within the notch 53 and locks the long leg of the shackle in the bore 16. The upper end of the locking bolt has a longitudinally extending comparatively shallow groove 56. This groove is adapted when the locking bolt is turned into its unlocked position to register with the inner end of the bore 21 and permits the lock pin to move inwards until the outer end thereof is disengaged from the notch 53 and releases the leg 11 so that it is free to move upwards in response to the action of the compression spring 19. When the spring 19 shifts the long leg 11 of the shackle upwards after release of the leg by inward movement of the pin 20 the outer end of the pin first traverses the channel 55 and then enters the groove 54 in the lower end of the long leg 11. The depth of the groove 54 is such that when the shackle is in its unlocked position the locking pin is held with the inner end thereof in the groove 56 and the locking bolt is thus locked against shift into its locked position by the spring 50. By reason of the fact that the groove 54 is an annular one the shackle is free when in its unlocked position to swing laterally about the axis of the long leg 11. The lower end of the notch 53 is curved so as to define a cam surface 57 leading to the upper end of the channel 55. When the locking bolt 18 is shifted into its unlocked position and the groove 56 is thus brought into registry with the inner end of the bore 21 this cam surface 57 in response to the action of the spring 19 moves the pin 20 inwards until the inner end thereof is in the groove 56 and its outer end is disengaged with or free from the notch 53.

When the padlock is in its locked position the lock dog 40 is disposed in the notch 41 and the lock pin 20 is interlocked with the groove 53 with the result that both legs of the shackle are held in fixed or locked relation in their respective bores in the casing 8. When it is desired to unlock the padlock it is only necessary to insert the key 33 into the key slot 22 of the lock plug 17 and then turn the key so as to rotate the plug into its unlocked position. When the key is inserted into the key slot the outer ends of the tumblers 25 are withdrawn from the grooves 29 and 30. As soon as the ends of the tumblers are withdrawn from the groove the plug is free so that it may be turned into its unlocked position. When the plug is turned into its unlocked position the locking bolt 18 as the result of the driving connection 75

that is afforded by the lug 47 and the shoulder forming abutment 49 is turned into its unlocked position. As soon as the lock dog 40 is disengaged from the notch 41 and the groove 56 is aligned with the bore 21 during turning of the locking bolt into its unlocked position the shackle is released with the result that the spring 19 forces it upwards into its unlocked position. During upward movement of the shackle into its unlocked position the pin 20 is shifted inwards as the result of the action of the cam surface 57 until the inner end thereof fits within the groove 56. When the lock is in its unlocked position the lock plug 17 may be returned to its locked position and the key withdrawn. When it is desired to lock the padlock the shackle is forced inwards. During inward movement of the shackle the lower end of the short leg 18 passes into the bore 15 and the lower end of the long leg of the shackle moves downwards in the bore 16. As soon as the notch 53 of the long leg encounters the outer end of the lock pin 20 and permits of outward movement of the lock pin the lock pin is moved outwards in response to the action of the spring 50 into its locked position wherein the outer end thereof is disposed in the notch 53. As soon as the lock pin 20 moves outwards and releases the locking bolt 16 the spring 50 rotates the locking bolt into its locked position wherein the lock dog 40 fits within the notch 41. If it is desired to remove the lock plug 17 from the padlock casing 8 for tumbler changing purposes or for any other reason, it is only necessary to unlock the padlock and then after swinging the shackle laterally so as to bring the short leg 18 thereof out of registry with the bore 15 to insert a pin through the bore and the tumbler receiving groove 39 into a position wherein it releases the crescent shaped holding device 30.

40 The herein described padlock consists of but a comparatively small number of parts and hence may be manufactured at a low and reasonable cost. It is extremely efficient as far as operation is concerned by reason of the fact that it includes the lock pin 20 which serves as a locking means for the long leg of the shackle.

45 The invention is not to be understood as restricted to the details set forth, since these may be modified within the scope of the appended claims, without departing from the spirit and scope of the invention.

Having thus described the invention, what I claim as new and desire to secure by Letters Patent is:

55 1. A padlock comprising in combination a casing having a pair of shackle receiving bores extending through the top face thereof and also having a third bore extending through its bottom face and intersecting one of the shackle bores and a cross-bore between and communicating with the upper end of the third bore and the other shackle bore, a longitudinally slideable U-shaped shackle having a long leg slidably and rotatably mounted in said other shackle bore and a short leg adapted in response to inward shift of the shackle from an unlocked position into a locked position to fit within said one shackle bore, a locking bolt rotatably mounted in the upper end of the third bore and adapted to be shifted from a locked position wherein it is interlocked with the short leg of the shackle into an unlocked position wherein such short leg is released, a locking pin slidably mounted in the cross-bore and shiftable outwards by the bolt into interlocked relation

with the long leg of the shackle when the shackle is in its locked position and the bolt is turned into its locked position, and a key-operable tumbler equipped plug mounted rotatably in the lower end of the third bore and connected to rotate the bolt into its unlocked position. 5

2. A padlock comprising in combination a casing having a pair of shackle receiving bores extending through the top face thereof and also having a third bore extending through its bottom face and intersecting one of the shackle bores and a cross-bore between and communicating with the upper end of the third bore and the other shackle bore, a longitudinally slideable U-shaped shackle having a long leg slidably and rotatably mounted in said other shackle bore and a short leg adapted in response to inward shift of the shackle from an unlocked position into a locked position to fit within said one shackle bore, a locking bolt rotatably mounted in the upper end of the third bore and adapted to be rotated from a locked position wherein it is interlocked with the short leg of the shackle into an unlocked position wherein such short leg is released, a spring for rotating the bolt into its locked position, a longitudinally slideable pin in the cross-bore, and shiftable outwards by the bolt into interlocking relation with the long leg of the shackle when the shackle is in its locked position and the bolt is rotated into its locked position, and so controlled by said long leg of the shackle that when the shackle is in its unlocked position it holds the bolt in its unlocked position against the force of the spring, and a key-operable tumbler equipped plug mounted rotatably in the lower end of the third bore and connected to rotate the bolt into its unlocked position. 15

3. A padlock comprising in combination a casing having a pair of shackle receiving bores extending through the top face thereof and also having a third bore extending through its bottom face and intersecting one of the shackle bores and a cross-bore between and communicating with the upper end of the third bore and the other shackle bore, a longitudinally slideable U-shaped shackle having a long leg slidably and rotatably mounted in said other shackle bore and a short leg adapted in response to inward shift of the shackle from an unlocked position into a locked position to fit within said one shackle bore, 40 a rotatable locking bolt in the upper end of the third bore adapted to be shifted from a locked position wherein it is interlocked with the short leg of the shackle into an unlocked position wherein such short leg is released and having a peripheral groove therein adapted to register with the cross-bore when the bolt is in its unlocked position, a spring for rotating the locking bolt into its locked position, a longitudinally slideable locking pin in the cross-bore shiftable outwards 45 by the bolt into interlocking relation with the long leg of the shackle when the shackle is in its locked position and the bolt is turned into its locked position by the spring, and controlled by the long leg of the shackle in such manner that when the bolt is turned into its unlocked position and the shackle is moved into its unlocked position it is shifted inwards into the groove in the plug and operates to hold the plug against return to its locked position by the spring, and a key-operable tumbler equipped plug mounted rotatably in the lower end of the third bore and connected to rotate the bolt into its unlocked position. 50

HENRY HANSEN.
